CONTAINER

Joseph N. Royal, Buffalo, N. Y., assignor, by
mesne assignments, to F. N. Burt Company,
Inc., Buffalo, N. Y., a corporation of Delaware

Application August 18, 1936, Serial No 96,628

14 Claims. (CL 229—5.5)

This invention relates to containers and especially to boxes made, preferably, wholly of paper material and used for containing and dispensing powdered material, particularly face powder.

5 Among the objects of the invention are:

The provision of an efficient and inexpensive paper container, or box, for dispensing face powder, and embodying a paper drum and a separate base adapted to be assembled and locked in powder retaining relation by the mere act of assembling these parts, and without the necessity for using other than paper or other similar sheet material.

15 The provision of a practical and simple construction of box of the character referred to and which readily lends itself to the powder filling operation without detracting from simplicity and effectiveness of the construction for interlocking the drum and base.

20 The provision of simple and efficient construction of a two-part powder box of the character referred to and involving a base and a drum, and in which the base serves also as an efficient closure for the drum.

25 The provision of a practical and efficient improved closure for a powder box of the character referred to.

30 The production of a powder box of paper material and simple and improved construction and wherein the powder is efficiently sealed until ready to be dispensed.

35 The production of a powder box of the character referred to having a drum and a base and having simple and improved construction for securing these parts together.

40 The provision of a practical and efficient construction of powder box of the character referred to wherein the drum and the base may be made strong and substantially rigid, and wherein, nevertheless, these parts may be easily secured together by the mere act of assembling.

45 The production of a box of the character referred to, wherein the construction of the securing devices between the drum and the base is promotive of easy alteration for adaptation to different box sizes.

50 The provision of a simple and practical drum of paper adapted to have automatic interlocking action with the base to which it may be applied. Other objects of the invention will in part be obvious and will in part appear hereinafter.

55 The invention accordingly comprises an article of manufacture possessing the features, properties, and the relation of elements which will be exemplified in the article hereinafter described

and the scope of the application of which will be indicated in the claims.

In the accompanying drawing forming a part of the specification and wherein similar reference characters refer to the same parts throughout the several views:

Fig. 1 is a perspective view, partly sectional, showing the drum and base of the container or box, in disassembled relation and also showing a box cover as usually employed; 10

Fig. 2 is a central vertical section illustrating the drum in assembled relation with one form of base which may be employed;

Fig. 3 is an enlarged sectional perspective partially diagrammatic view of a fragment of the drum for more clearly disclosing detail construction;

Fig. 4 is a sectional view similar to that of Fig. 2 illustrating a drum assembled with a somewhat modified form of base; 20

Figs. 5 and 6 are enlarged sectional views illustrating details of construction.

Referring now more specifically to the drawing, the drum part of the box is indicated at *a*, the base part being indicated at *b*. At *c* is indicated 25 a box cover which may be employed. These parts are preferably made of paper material, although it is to be understood that in respect to certain of the box elements, as for instance the base herein described, other materials may be found useful, as for instance wood, metal, Bakelite, or other 30 relatively hard materials. The numeral 1 indicates the main body or lateral wall of the drum, the drum having some resilience transversely of its longitudinal axis. As illustrated, the drum 35 wall *1* may be cylindrical and is intended to surround and fit closely the flange *2* of the base *b*. Each of these parts, namely, the drum *a* and the base *b*, are provided with devices for retaining them in assembled relation. 40

Referring to the drum *a*, the lateral wall *1* thereof may be composed of a number of plies, laminations, or coils of paper in contact with each other, the wall being built up so as to be substantially rigid against longitudinal compression in the plane of the wall. The wall *1* is provided at its lower end with a retainer device consisting of a continuous circumferential retainer rib or shoulder *3*, this shoulder extending inwardly of the drum and running continuously around 45 its lower edge. In the embodiment illustrated, the retainer shoulder *3* is provided by crimping the lower edge of the drum wall *1*, this lower edge being sufficiently flexible for the purpose. In practice, the wall *1* includes two plies or layers 50

55

4 and 5 of relatively thin paper material, these plies projecting sufficiently below the other plies of the wall 1, thereby forming a flexible lower edge of the drum readily adapted to be crimped. 5 However, it is to be understood that in its broader aspects, the invention is not limited to the provision of the extended ends of the plies 4 and 5, although this is a preferable construction. The entire thickness of the drum wall at its lower 10 edge may be crimped without departing from the broader aspects of the invention.

In practice, the circumferential periphery 6, of one of the plies 5, is turned over the peripheral edge of the other ply 4, to strengthen the ultimate 15 edge of the crimp or shoulder. The crimp provides a rounded shoulder at the lower edge of the drum and continuously therearound, the lower edge of the drum thus having a retainer shoulder which is resilient and flexible. If desired, the 20 paper of the crimped part may be sized to increase its density and resilience. The inner edge of the crimp or rib 3 preferably somewhat overlaps the outer cylindrical surface of the flange 2 of the base b, so that, in the assembling operation, the rounded crimp or shoulder eases over the corner 7 of the flange 2, and resiliently yields outwardly until the drum attains its ultimate assembled relation to the base b, whereupon the 25 crimp springs inwardly to cooperate with the retainer device on the base and hold the drum and base together in assembled relation.

In the form illustrated in Figures 1 and 2, the drum base, or base part, or closure part, b has the flange 2 resting on the head 8 of the base 30 and upstanding therefrom, this flange being a continuous ring disposed inside the marginal edge of the base, and being of solid, relatively thick structure and substantially rigid in its own plane longitudinally of the axis of the drum. 35 In the embodiment illustrated the flange 2 is of laminated structure and includes the two circular laminations, or relatively thick paper strips 9 and 10, which may be adhesively secured together, the lower edge 11 of the lamination 40 10 being related to the head 8 so as to provide a retainer shoulder, continuous circumferentially around the base and, in cooperation with the lamination 9 and said head, providing the retainer recess or groove 12 which is bounded by different laminations. 45

To guard against the escape of powder through the joint between the lamination 9 and the head 8, a powder seal is provided. In the embodiment illustrated, a flexible strip 13 of thin paper or other suitable sealing strip material is disposed across said joint, this strip extending peripherally around the base and being adhesively secured to the head of the base and to the flange 2. Preferably the strip 13 has its upper margin 50 held between the flanges 9 and 10, the strip following the wall of the recess 12 along the lamination 9 and the upper face of the head 8, and thence extending around the outer edge of the head 8 where it may serve to give a finished 55 appearance to the edge of the head. The material of the sealing strip 13 is preferably relatively soft, so that where the retainer device or crimp 3 on the drum contacts therewith, some sealing effect may be attained. Thus, in addition to the sealing effect on the joint between the lamination 9 and the head 8, should any powder seep between the lamination 10 and the wall of the drum it will tend to be prevented from 60 escaping by the contact between the crimp or shoulder and the soft sealing strip. This sealing 65

effect is augmented by the resilient character of the crimp, which presses tightly into the or across the groove or recess 12 and against the sealing strip 13. 70

The character of the base, or closure part, of the drum may be such as to be non-yielding to the pressure of interlocking between the retainer devices of the drum and base, and the base forms a substantially solid bottom, or base portion, of the box. The marginal portion 14 10 of the head 8, which is outside the drum, cooperates to form a member or wall of the retainer recess on the base, and lies in close contact with the retainer shoulder 3 of the drum and underneath such shoulder. 15

In the modification illustrated in Fig. 4, the base may be generally flat as shown, and composed of a plurality of superposed plies of laminations of relatively heavy, solid paper material, such as pasteboard or paper and board, or the other material hereinbefore mentioned. This generally flat base may include the three plies, or laminations 15, 16, and 17, forming a plurality of solid, closure disks, which are firmly secured together in relatively superposed relation to each other. Suitable adhesive may be used for such purpose. In this modification, the retainer recess, indicated at 18, is formed by offsetting the edges of the closure disks 15, 16 and 17 relative to each other as indicated in Fig. 6, the margins of the disks 15 and 17 each arranged to protrude outwardly beyond the margin of the intermediate disk 16 as indicated, thus forming the retainer recess 18. The margin of the disk 17 protrudes beyond those of the disks 15 and 16 to position under the lower end of the drum 20, as indicated at 19, which drum may be similar in construction to the drum described in connection with Figs. 1 and 2, and is provided at its lower edge with a similar retainer shoulder 3 40 or retainer crimp extending continuously around said edge. 30

In each modification the base protrudes from the open end of the drum, and the head of the base, illustrated in Fig. 2, also the bottom lamination of the base illustrated in Fig. 4, extends to position under the lower crimped edge of the drum, thus being adapted to limit the movement of the drum onto the base and cooperate with the crimp to assist in obtaining a tight joint between the base and drum. In the form illustrated in Fig. 4, the disks 15, 16 and 17 are of different diameters concentrically arranged and secured together so as to provide the retainer recess 18 and the extended margin 19 of the bottom disk or lamination. Different drums having crimps 3 of larger or smaller diameters may be quickly accommodated by using disks of different thickness to provide the retainer recess 18 of suitable dimension to accommodate any 50 particular thickness of the crimp. In the recess 18, sealing material of any suitable character may be employed, as for instance, a strip of relatively soft, thin paper, similar to the sealing strip 13 and lying in the recess and adhesively secured in place around the base, as indicated at 30, in Fig. 6, and this strip may continue around the edge of the portion 19. 55

By constructing the flange 2 of the base of superposed plies or laminations, the grain of the 70 flexible paper materials, of which the different plies may be composed, may be arranged at angles to each other to lessen any tendency of the flange to warp or get out of shape, and the flange may be strengthened by using one or more plies 75

of selected, strong material. Also in addition to the provision of the retainer recess or groove 18 in the base, illustrated in Fig. 4, tendency of the assembled disks to warp is lessened by the laminated structure and by selecting disks of suitable material a strong and rigid base may be made which is not objectionably thick.

In the preferred construction of the box, the drum head 21 consists of a readily frangible sheet, such as tissue paper, translucent or transparent cellulosic material or other easily broken material, stretched over the top or open end of the lateral wall 1 of the drum and secured throughout its circumference to said wall, so as to form a powder-tight joint. In the present embodiment the frangible sheet 21 may have down-turned edges secured between and adhesively secured to laminations of the drum wall 1, as indicated at 22.

When the drum and base are assembled with the retainer devices in cooperative relation, a complete, closed container part is formed, at one end of which is the base and at the other end is the frangible sheet 21. In practice and especially to protect the frangible sheet against accidental puncture or breakage, and to protect the assembled elements over all, a box cover may be employed. This box cover may consist of a head 23 and a solid flange 24, which when applied over the assembled base and drum will surround and protect the lateral wall of the drum and the head 21, and may rest upon the projecting margin 14 of the bottom of the base.

In using the box, the drum is filled with powder before it is assembled with the base. After filling the drum the base is applied thereto and slid into the open end of the drum past the continuous shoulder or crimp 3, the rounded shape of the crimp facilitating the entry of the leading edge of the base into the opening in the drum, the shoulder on the drum being flexed outwardly by contact with the lateral face of the base. By continuation of the assembly movement the retainer device or shoulder 3 of the drum will eventually move beyond the retainer shoulder of the base and will spring into interlocking engagement with the latter shoulder and into the retainer recess or groove 12. The outwardly extending margin 14 or 19 of the bottom member of the base will limit the extent of relative assembling movement between the base and drum, and on account of the resiliency and flexibility of the crimp, said crimp may also be slightly deformed and will resiliently act to press itself closely against the contacting walls of the retainer recess or groove in the base so as to form a joint largely tending to prevent the escape of powder between the retainer devices of the drum and base. Thereupon the box cover may be applied over the head and lateral walls of the drum and detachably secured thereto in any suitable manner, if desired. To dispense the powder, the protective box cover is first removed. This will expose the frangible head 21 which may then be easily broken as by pressing the finger against the head 21, to obtain access to the powder.

In the exemplary modifications of the invention herein disclosed, it will be noted that the outer peripheral retainer grooves 12 and 18 are positioned adjacent to the lower edges of the side wall 1 of the drum when the latter is in assembled relation with the base or closure member of the container. Also the retainer or interlocking shoulder 3 of the drum is positioned for interlocking engagement with the retainer grooves

which, for this purpose, are preferably formed as shown with upper and lower shoulders cooperating with the interlocking element 3.

Since certain changes may be made in the article herein described and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. In a container of the character described, the combination of a drum part having an opening at one end and a closure part for said opening, each of said parts having a circumferentially continuous retainer device, the retainer devices cooperable to interlock with each other and secure the closure in the opening by assembling movement between the parts, one of said parts having laminations off-set relative to each other at their edges to form said retainer device thereon and a powder sealing strip secured between laminations of said part and disposed in contact with the retainer device of the other part in the assembled relation of said parts.

2. In a container of the character described, the combination of a drum part having an opening, and closure means for closing said opening, said closure means including a closure part having relatively superposed, solid, upper, lower and intermediate closure disks secured together, the edges of said intermediate disk being off-set inwardly relative to the other disks to provide a continuous circumferential retainer groove having upper and lower shoulders.

3. In a container of the character described, the combination of a drum part having an opening, and closure means for closing said opening, said closure means including a laminated, solid closure part adapted for insertion in said opening and having in its edge a continuous, circumferential, retainer recess between different laminations, for reception of the edge of said drum part, said drum part being resilient and having at its open end a circumferentially continuous, rounded retaining shoulder adapted to enter said recess and resiliently maintain close contact with the wall of said recess.

4. In a container of the character described, the combination of a drum part having an opening, and means for closing said opening and retaining the closing means in closed relation, said means including a laminated, solid closure part adapted for insertion in said opening and having in its edge a continuous, circumferential, retainer recess between different laminations, for reception of the edge of said drum part, said drum part being resilient and having at its open end a circumferentially continuous, rounded retaining shoulder adapted to enter said recess and resiliently maintain close contact with the wall of said recess, one of said laminations having an outwardly extending marginal portion extending beyond the adjacent lamination and lying beneath and in contact with said shoulder in the closed relation between the drum part and closure part.

5. In a container of the character described, the combination of a drum, a substantially rigid base having a head and an upstanding, continuous, laminated, substantially rigid flange resting on said head inside the marginal edge of the head, the lower edge of the outer lamination terminating short of the next inner lamination to provide

a retainer recess between said outer lamination and said head in the outside face of said base.

6. In a container of the character described, the combination of a drum, a substantially rigid base having a head and an upstanding, continuous, laminated, substantially rigid flange resting on said head inside the marginal edge of the head, the lower edge of the outer lamination being related to provide a retainer recess between the latter lamination and said head in the outside lateral face of said base, and a strip of flexible, powder sealing material sealing said recess from the joint between said flange and head.

7. In a container of the character described, the combination of a drum, a substantially rigid base having a head and an upstanding, continuous, laminated, substantially rigid flange resting on said head inside the marginal edge of the head, the lower edge of the outer lamination being related to provide a retainer recess between the latter lamination and said head in the outside, lateral face of said base, said drum having an uprightly rigid, continuous wall closely fitting said flange and a resilient, continuous, retainer-crimp carried by and of greater flexibility than said continuous wall and engaging in said retainer recess.

8. In a container of the character described, the combination of a drum, a substantially rigid base having a head and an upstanding, continuous, laminated, substantially rigid flange resting on said head inside the marginal edge of the head, the lower edge of the outer lamination being related to provide a retainer recess between the latter lamination and said head in the outside, lateral face of said base, said drum having an uprightly rigid, continuous wall closely fitting said flange and a resilient, continuous, retainer-crimp of flexible material engaging in said retainer recess, said wall being of laminated structure, and having a plurality of laminations of thin flexible material protruding below the others and providing the material for said retainer-crimp.

9. In a container of the character described, the combination of a drum, a substantially rigid base having a head and an upstanding, continuous, laminated, substantially rigid flange resting on said head inside the marginal edge of the head, the lower edge of the outer lamination being related to provide a retainer recess between the latter lamination and said head in the outside lateral face of said base, and a strip of flexible, powder sealing material sealing said recess from the joint between said flange and head, and held between laminations of said base and to said head.

10. In a container of the character described, the combination of a drum, a substantially rigid base having a head and an upstanding, continuous, laminated, substantially rigid flange resting on said head inside the marginal edge of the head, the lower edge of the outer lamination being related to provide a retainer recess between the latter lamination and said head in the outside lateral face of said base, and a strip of flexible, powder sealing material sealing said recess from the joint between said flange and head, said drum having an uprightly rigid, continuous wall closely

fitting said flange and a resilient, continuous, retainer-crimp of flexible, sized material engaging in said retainer recess.

11. In a box of the character described, the combination of a drum-wall, open at each end, and a drum-base adapted for insertion in one end of the drum wall, for closing the opening in the drum, each of said parts being substantially rigid longitudinally of the drum, each part having a continuous, circumferential, retainer shoulder, the shoulders cooperable resiliently to interlock with each other by assembly movement between said parts, and a cover sheet of frangible material stretched over the opposite open end of the drum wall and secured thereto throughout its circumference, said base having laminations one of which provides a retainer shoulder inside said opening, and another of which cooperates with the lamination inside the opening to provide a retainer recess on the base for interlocking with said circumferential shoulder on the drum-wall.

12. In a box of the character described, the combination of a drum-wall and a drum-base adapted, the one for insertion and retention in the other, for closing the opening in the drum, each of said parts being substantially rigid longitudinally of the drum, each part having a continuous, circumferential, retainer shoulder, the shoulders cooperable resiliently to interlock with each other by assembly movement between said parts, the shoulder of said drum wall being a continuous, circumferential, crimp of an edge thereof, said crimp being of greater flexibility than said drum wall.

13. In a box of the character described, the combination of a drum-wall and a drum-base adapted, the one for insertion and retention in the other, for closing the opening in the drum, each of said parts being substantially rigid longitudinally of the drum, each part having a continuous, circumferential, retainer shoulder, the shoulders cooperable resiliently to interlock with each other by assembly movement between said parts, the shoulder of said drum wall being a continuous, circumferential, crimp of an edge thereof, said crimp being flexible and of laminated structure having one lamination extending beyond and turned over the edge of an adjacent lamination to form a retaining bead, the retainer shoulder on said base being unyielding to pressure from said crimp.

14. In a container, in combination, a drum part having a side wall and a lower opening, and closure means for closing said opening, said closure means including a closure part having laminations, one of which terminates at one edge portion short of an adjacent lamination to form at the outer periphery of the closure part a groove with an upper shoulder and positioned adjacent to the lower edge of said drum side wall when in assembled relation, said closure part having a bottom member with a peripheral marginal extension underlying the lower end of said drum side wall and forming a lower shoulder for said groove, and an interlocking member on said side wall interlocking in said groove.

JOSEPH N. ROYAL.
